INKSTAND

Martin S. Pollock, East Chester, N. Y.

Application September 17, 1943, Serial No. 502,751

6 Claims. (Cl. 120—57)

This invention relates to inkstands generally and has particular reference to a construction of this type in which novel and useful features are included in a simplified assemblage.

Objects of the invention therefore include the provision of an inkstand which, serviceable under varying conditions, is capable of being manufactured from one of various materials, including those of synthetic or plastic types, and at a reasonable cost.

It is the custom of users of pens, as when dipping them in inkwells, as by insertion of a pen point portion through the dip aperture of a cover or the like, to make the insertions of an average or uniform depth, and another of the objects of this invention is to provide an inkstand in which a section thereof is movable in such manner that when a pen is inserted as aforesaid, the distance the pen dips in the reservoir of the stand can be kept constant by proper adjustment of the top.

Inventive features of this disclosure are found in a base inkstand section having a convex top, and a cover section, in which is a dip aperture, having a concave under face.

The cover, while maintaining the same engaging areas between the two sections, is relatively movable for bringing said aperture to a high part or a low part of said convex top, with the result set forth.

In accordance with yet another object at present involved, a uniform pressure is maintained between the two stand sections, and for this purpose a spring element having a novel permanent anchorage is used on the base.

With the above indicated objects and advantages in view, as well as others which will herein-after appear, the invention resides in certain novel constructions and arrangements of parts, the essential features are herein clearly described and illustrated in the accompanying drawing, in which:

Fig. 1 is a top plan view of an inkstand constructed in accordance with this invention;

Fig. 2 is a front elevation thereof;

Fig. 3 is a section on the line 3—3 of Fig. 1;

Fig. 4 is a fragmentary plan view, similar to Fig. 1, but with parts removed;

Fig. 5 is an underside view of a cover section; and

Fig. 6 is a fragmentary longitudinal section in which are illustrated specific engaging parts.

As shown in said drawing, a base section 10 has, rising from lower side portions 11 thereof, a central body part 12, which has a longitudinally disposed convex surface, said surface, at any trans-

verse line being straight as seen in Fig. 2. The side wings 11 have therein longitudinal recesses for holding articles such as pens, and in the body portion 12 is a medial elongated cavity 13 or ink recess.

Gravitationally resting on the base 10 is a top cover 14, the under face 18 of which is concave and adapted to frictionally engage the convex surface 12, for controlled sliding movement, or 10 for frictional gripping relation thereon. In the front central part of said cover is a pen dip aperture 15, and said front part, as at its leading edge 16, is relatively deep. The cover 14 tapers gradually in depth to its after part 17, therefore giving said cover some of the characteristics of a conventional air foil section, and this tapering is also found transversely, the front part 16 being wider than the after part 17.

A cover retaining spring 20 is formed with a 20 face front end having an outwardly turned tip 21 and an anchoring end having portions 22, 23, 24, which permanently grip a cross bar member 25 of the base 10, said member being provided by an angular opening 26 in said base. As seen in Figs. 1, 3 and 4, a recess 27 in the base 10, provides an emplacement for the outer end part 24 of the retaining spring 20, and the lower surface of the spring part 23 is flush with the lower face of the base 10.

30 The tip 21 of the spring 20 exerts a light holding pressure against the cover 14, and other features of said cover reside in a stop being formed therefor, at one limit of its travel, when the end 17 reaches backwardly to the uppermost part of the spring portion 22, Fig. 3. If at any time the cover 14 is moved forwardly until its front edge 16 is stopped by reaching the ground or bottom level of the base 10, it is noted that then the end 17 is still under the tip 21. Therefore no displacement error or undue removal of the cover 14 can normally take place, during fore and aft travel thereof, and such travels may be brought about by use of the pen point portion in the aperture 15.

40 Such travel is effective to bring the aperture 15, as at its top part, where the pen being used can be watched, near to or distant from an ink level in the reservoir 13. Thus, as seen in Fig. 3, at an ink level 30, a forward position of the cover 14 results in a pen 31 being dipped for receiving the correct amount of ink; and in a more rearwardly position of said cover, when the aperture 15 is directly above a dotted line pen 32, said pen is so positioned as to receive the correct amount 50 of ink at a level 33.

Relative movements of the aforesaid cover and base are facilitated because of a reduction during the movement of the engaging faces. This featuring, moreover, as here to be described, gives the cover 15 latched positions on the face 10.

In said base are a pair of transversely aligned notches 35, and a second pair 36. The cover 14 has thereon a pair of lugs 40, 41 (Fig. 1), and on the body 12, marginal to the reservoir 13 are portions (Fig. 4) 42, 43, identified as tracks.

Therefore, when the lugs 40, 41 are disposed on the notches 35, the cover 14 is in a latched position, as in Fig. 1. To move the cover, as backwardly, said lugs are lifted with the cover and placed on the tracks 42, 43; then as the cover is moved backwardly said lugs drop into the notches 35, and the cover is latched with an aperture 35 in position for receiving the pen 32, shown in dotted lines. The ribs 37, 38 may be deeper than the lugs 40, 41.

As seen on Fig. 5, the cover 14 is identical with the cover of Fig. 1, although of reduced proportions. In Fig. 1, both ribs 37, 38 engage freely for movement along the side faces of the recess 13, but with the narrower structure of Fig. 5 only one rib or lug thereof is engageable against the boundary side of the recess 13, at any time. Thus, the latching condition is brought about with the Fig. 5 structure, as by engaging one lug 41 thereof in a base recess 35 or 36. A latched structure of this type is seen in Fig. 6.

I claim:

1. An inkstand comprising in combination a base having a convex top surface, an ink recess within said base with a cover for said base having a pen tip aperture and having its concave under face resting on said top surface of said base, said base having a lowermost and uppermost anchorage and means held by said anchorage and engaging said cover on the top thereof whereby when the ink in said recess is at a high level the said aperture in the cover may be moved to the apex for limitedly placing a pen nib therein to reach ink at the high level and when the ink is at a low level the cover may be moved endwise to lower said aperture nearer the low level of said ink.

2. An inkstand comprising in combination a base having a convex top with a cover having a lower concave face resting on said top, a recess in said base for ink, said base having a lowermost integral bar, and spring means having an end anchored on said bar and an end pressing said cover on the top, a pen aperture in said cover, means for limiting the movement of said cover to a high and low position whereby when the ink in said recess is at a high level the said aperture in the cover may be moved to the apex for limitedly placing a pen nib therein to reach ink at the high level and when the ink is at a low level the cover may be moved endwise to lower said aperture nearer the low level of said ink.

3. An inkstand comprising in combination a

face having a convex top, said base providing an ink reservoir with an open top with a cover having a concave under face resting on said top around the opening, said base having a lowermost integral bar, said cover having therein above the opening a pen dip aperture, means fixedly held on said bar and having a resilient portion pressing said cover on the top thereof, means for limiting the movement of said cover to a high and low position whereby when the ink in said recess is at a high level the said aperture in the cover may be moved to the apex for limitedly placing a pen nib therein to reach ink at the high level and when the ink is at a low level the cover may be moved endwise to lower said aperture nearer the low level of said ink.

4. An inkstand comprising in combination a base having a convex top and providing therein an ink reservoir, said top having in the boundary of the reservoir notches, with a cover having a concave face movable on said top, lug means on said face, said means adapted to holdingly enter said notches, a pen aperture in said cover, means for limiting the movement of said cover to a high and low position whereby when the ink in said recess is at a high level the said aperture in the cover may be moved to the apex for limitedly placing a pen nib therein to reach ink at the high level and when the ink is at a low level the cover may be moved endwise to lower said aperture nearer the low level of said ink.

5. An inkstand comprising in combination a base having a convex top surface and providing therein an ink recess, said top having in the boundary of the recess plural notches with a cover having a concave under face with portions thereof movable on said notches around the recess, and a lug reaching downwardly from said under face, the lug being movable along said boundary, whereby said lug may be guided into a selected notch to latchingly hold said cover, a pen aperture in said cover, means for limiting the movement of said cover to a high and low position whereby when the ink in said recess is at a high level the said aperture in the cover may be moved to the apex for limitedly placing a pen nib therein to reach ink at the high level and when the ink is at a low level the cover may be moved endwise to lower said aperture nearer the low level of said ink.

6. An inkstand comprising in combination a base having a convex top and providing a longitudinal ink recess and an elongated thin cover having a concave face resting on said top and being longer than the recess, the cover having therein a pen dip aperture, whereby the aperture may be moved to the apex of said top for limitedly placing a pen nib therein to reach ink having a high level in the recess, so that when the ink level is low said cover may be moved in endwise to lower said aperture to a position near the ink at said low level.

MARTIN S. POLLOCK.
